(57) **CLAIM**

I claim the ornamental design of a photo luminescent resin angel, as shown and described.

DESCRIPTION

FIG. 1 is a perspective view of photo luminescent resin stone angels, showing my new design;

FIG. 2 is a front elevational view of the invention;

FIG. 3 is a rear elevational view of the invention;

FIG. 4 is a left-side elevational view of the invention;

FIG. 5 is a right-side elevational view of the invention;

FIG. 6 is a top plan view of the invention; and,

FIG. 7 is a bottom plan view of the invention.

The broken lines shown in FIG. 1 depict environmental subject matter only and form no part of the claimed design.
